TWEEZERS

William R. Tuttle and William J. Beldue, Rochester, N. Y., assignors to The Kurlash Company, Inc., Rochester, N. Y., a corporation of New York

Application February 6, 1948, Serial No. 144,323

Term of patent 14 years

(Cl. D86—10)

To all whom it may concern:

Be it known that we, William R. Tuttle and William J. Beldue, citizens of the United States of America, and residents of Rochester, county of Monroe, State of New York, have invented a new, original, and ornamental Design for Tweezers, of which the following is a specification, reference being had to the accompanying drawing, forming part thereof.

Fig. 1 is a side elevational view of the tweezers, showing my new design;

Fig. 2 is a top plan view of the same, and

Fig. 3 is an end view of the same, looking from the right of Fig. 1.

We claim:

The ornamental design for tweezers, substantially as shown.

WILLIAM R. TUTTLE.
WILLIAM J. BELDUE.
